ABSTRACT OF THE DISCLOSURE

The present invention is directed to a machine and method for packaging articles. A cutter assembly is provided for severing said articles from a blank. Receptacle means are mounted below the cutter assembly and guide means, in the form of pins are provided for guiding said severed articles into said receptacle means. The guiding means include aligning pins for maintaining the relative positions of said articles to each other during the travel of the articles from the severing mechanism into the receptacle means. The filled receptacle is moved from under the cutter means and the articles are transferred to a carton without changing the relative position of the articles to each other.

The present invention relates to an improved article package for articles, for example tableware such as spoons, forks, knives and the like, and an improved machine and method for forming said article package.

Tableware, such as knives, forks, spoons and similar articles which are primarily adapted to be disposed after use are usually manufactured from a plastic by injection molding and are packaged in bulk in shipping cartons. In general, these articles are deposited in shipping cartons in random fashion so that there is a considerable amount of wasted space within the cartons which necessitates the use of larger cartons and increases shipping, storage and labor costs. Furthermore, packaging plastic tableware in random fashion sometimes causes breakage.

The present invention avoids these objections and has for one of its objects the provision of an improved package of articles, such as plastic tableware, which has the articles uniformly located therewithin.

Another object of the present invention is the provision of an improved packaging machine which will permit more table articles to be packaged in a carton per unit volume than heretofore possible.

Another object of the present invention is the provision of an improved packaging machine which automatically packages articles uniformly in a carton.

Another object of the present invention is the provision of an improved method of packaging articles in predetermined uniform fashion within a carton.

Another object of the present invention is the provision of an improved packaging machine for packaging articles in uniform fashion in a carton at greater speeds.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawings forming a part of the specification, wherein:

FIG. 1 is a rear and side perspective view of a machine made in accordance with the present invention;

2

FIG. 2 is a front and side perspective view of the machine shown in FIG. 1;

FIG. 3 is a front elevational view of the frame of the machine with some of the operative elements removed for clarity;

FIG. 4 is a side elevational view of the machine as shown in FIG. 3;

FIG. 5 is a side elevational view of the blank dropping, indexing and feeding means;

FIG. 6 is a sectional view taken along line 6—6 of FIG. 3;

FIG. 7 is a sectional view taken along line 7—7 of FIG. 3;

FIG. 8 is a sectional view taken along line 8—8 of FIG. 3;

FIG. 9 is a sectional view taken along line 9—9 of FIG. 3 showing the pin holding rods in extended position;

FIG. 10 is a top elevational view similar to FIG. 9 showing the pin holding rods in retracted position;

FIG. 11 is a sectional view taken along line 11—11 of FIG. 3;

FIG. 12 is a sectional view taken along line 12—12 of FIG. 3;

FIG. 13 is a sectional view taken along line 13—13 of FIG. 5;

FIG. 14 is a sectional view taken along line 14—14 of FIG. 13;

FIG. 15 is a sectional view taken along line 15—15 of FIG. 5;

FIG. 16 is a sectional view similar to FIG. 15 showing the operation of the blank stepping means;

FIG. 17 is a sectional view taken along line 17—17 of FIG. 5;

FIG. 18 is a sectional view taken along line 18—18 of FIG. 5;

FIG. 19 is a detailed elevational view showing the blank immediately before articles are severed therefrom;

FIG. 20 is a detailed elevational view similar to FIG. 19 showing the blank after the articles have been severed;

FIG. 21 is an elevational view showing the blank ejecting mechanism;

FIG. 22 is a sectional view taken along line 22—22 of FIG. 18 showing the position of the blank before it is fed to the severing mechanism;

FIG. 23 is a sectional view similar to FIG. 22 showing the position of the blank after the first frame thereof is fed to the severing mechanism;

FIG. 24 is a sectional view taken along line 24—24 of FIG. 19;

FIG. 25 is a detailed section showing the position of the cutter punch before the severing operation;

FIG. 26 is a sectional view taken along line 26—26 of FIG. 20;

FIG. 27 is a detailed section showing the severing operation;

FIG. 28 is a perspective view showing the severing operation;

FIG. 29 is a sectional view showing the position of the guiding pins after the receptacle has been filled;

FIG. 30 is a similar view showing the position of the pins after they have been withdrawn from the receptacle;

FIG. 31 is a top plan view of the receptacle for receiving the articles;

FIG. 32 is a side elevational view of the receptacle shown in FIG. 31;

FIG. 33 is a diagrammatic view showing the manner for initially moving the receptacle out of the machine after it is filled with articles;

FIG. 34 is an end view the position of a carton immediately before it is lowered over the receptacle;

FIG. 35 is a view similar to FIG. 34 showing the position of the carton after it is lowered over the receptacle;

FIG. 36 is a detailed view showing the relative position of the carton and the receptacle after they have been inverted;

FIG. 37 is a detailed view showing the mechanism for moving the carton out of the receptacle;

FIG. 38 is a detailed view showing filled carton after it has been moved out of the receptacle;

FIG. 39 is a perspective view showing the filled carton with articles packaged therein in accordance with the present invention;

FIG. 40 is a perspective view of a spoon which may be packaged with the present invention; and

FIG. 41 is a plan view of the blank from which the articles are severed.

The dimensions of the invention as illustrated in the drawings are substantially proportional to the dimensions of the machine as actually built.

For convenience the invention will be described under separate headings below.

ARTICLES TO BE PACKAGED

The present invention provides an improved packaging mechanism for articles, such as tableware, an example of which is the spoon 1 shown in FIG. 40. The spoon 1 may be made of a plastic or other similar material and comprises a bowl portion 2 and a handle portion 3. The bowl portion 2 is wider than handle portion 3 so that a pair of opposed bearing surfaces 4 are formed at the juncture between the handle 3 and the bowl 2. Preferably, an opening 5 is formed in the rear end of the handle 3.

It will be understood that the spoon 1 shown in the drawing is merely representative of the article with which the present invention may be used. The invention may be used with other items of tableware, such as forks, knives, etc. and may also be used with articles other than tableware.

It will be thus understood that when the expression "spoon" or "tableware" is used herein, it is intended to denote and cover not only spoons or other tableware but any other article with which the present invention may be used.

THE BLANK

As shown in FIG. 41, spoons 1 or similar articles are formed in a molding machine (not shown) in the form of a blank 10 having an outer border 11. The outer border 11 comprises side members 12, end members 13 and 14, and a divider member 15 which separates the blanks 10 into a first frame 16 having a first set of spoons 1 and a second frame 17 having a second set of spoons 1.

Each frame 16 or 17 has a set of spoons 1 mounted thereon by a web 18 extending from the handle 3 thereof. The spoons 1 are so arranged that the bowl portion 2 of adjacent spoons 1 face in opposite directions. Thus the bowl 2 of one spoon is adjacent the handle 3 of an adjacent spoon. This permits a greater number of spoons 1 per unit to be formed thus permitting a reduction in material and size of machine and permitting packages to be smaller and more compact, as well be set forth in greater detail hereinbelow.

Each side border member 12 of the border 11 has a pair of spaced centering slots 19 with each centering slot 19 being positioned at about midpoint of each frame 16. The end border members 13 and 14 each has a pair of spaced bearing surfaces 20 extending therefrom and the divider 15 has a pair of spaced openings 21 into which a plurality of bearing surfaces 22 extend. The bearing surfaces 20 and 22 on each side of the center line of the blank 10 are longitudinally aligned with each other.

THE PACKAGE

The improved package 30 formed by the present invention is shown in FIG. 39 and comprises a carton 31 having the usual closing flaps 32. The spoons 1 are packaged within the carton 31 one on top of the other to form a stack 35. The bowl portions 2 of adjacent stacks 35 of

spoons 1 face in opposite directions. Thus, the bowls 2 of a stack of spoons 1 face in the same direction as the handles 3 of an adjacent stack 35 of spoons 1. In this manner, more spoons may be packaged per unit volume since the greater part of the available space in a carton is utilized and there is no wasted space within the carton 30. This results in reduced shipping, handling and storage costs since smaller cartons may be used.

GENERAL DESCRIPTION OF MACHINE

10 The machine for carrying out the present invention is shown in FIGS. 1 and 2 and comprises a frame 40. The blanks 10 are formed in a molding machine (not shown) and are fed to a dropping mechanism 42 by means of a conveyor 41. The dropping mechanism 42 aligns the blanks 10 and drops them one-by-one into an indexing mechanism 43. The indexing mechanism 43 is adapted to drop the blanks 10 in one-by-one relationship to a feeding mechanism 44 comprising a feed plate 45 and a pair of feed chains 46 located on opposite sides of the feed plate 45.

The feed belts 46 are adapted to successively feed the first and second frames 16 and 17 of the blank 10 to a cutter mechanism 47 positioned above a receptacle 48. The cutter mechanism 47 is adapted to sever the webs 18 which connect the spoons 1 to the border of the blanks 10, as is shown in FIGS. 24 and 26 so that the severed spoons 1 drop into the receptacle 48.

20 A guide pin assembly 49 comprising a plurality of up-standing guide pins 121 and 122 are provided below the cutter mechanism 47 and extend into and through the receptacle 48. The guide pins 121 and 122 bear against the spoons as they are being severed and keep them aligned after they are severed. This guide pin assembly 49 maintains the spoons 1 in the same orientation while they are dropping downwardly into the receptacle 48.

25 In this manner when the spoons 1 are severed by the cutter mechanism 47 the spoons will travel downwardly along the guide pins 121 and 122 without changing their orientation and will be assembled in the receptacle 48 in stacks which are oriented in the same manner in which they are formed, i.e. with the bowls of adjacent stacks of spoons facing in opposite directions.

30 After the blank 10 has the spoons in both frames 16 and 17 severed, it is removed from the machine by take off rollers 85 and dropped into a bin 88.

35 When a sufficient number of spoons has been assembled into stacks in the receptacle in this manner, the guide pin assembly 49 is lowered until the guide pins 121 and 122 are completely withdrawn from within the receptacle 48 (FIG. 30). The receptacle 48 is then moved laterally out from beneath the cutter mechanism 47 (FIG. 33) until it underlies an inverted carton 31 located on the side of the frame (FIG. 34).

40 The inverted carton 31 is lowered by the lowering mechanism 50 until it completely covers the receptacle 48. During this entire operation the spoons remain oriented relative to each other so that the bowls of adjacent spoons face in opposite directions.

45 When the carton 31 completely encases the receptacle 48, the carton 31 and the receptacle 48 are rotated 180° and inverted so that the spoons are transferred from the receptacle to the carton 31 without changing the orientation of the spoons relative to each other.

50 The filled carton 31 is then pushed out of the receptacle 48 and removed. The receptacle 48 is again rotated 180° and moved back to a position below the cutter mechanism and the operation is repeated.

55 The filled carton 31 has the spoons located therein in the same orientation as they were originally manufactured, i.e. with the bowls of adjacent spoons facing in opposite directions. In this manner more spoons may be packaged in a carton per unit volume than heretofore possible since the spoons are not placed therein in random fashion and all of the available space in the carton is substantially completely filled up by the spoons.

BLANK DROPPING MECHANISM

The blank dropping mechanism or bin 42 is shown in FIGS. 5, 13 and 14, and comprises a pair of end standards 60 and side walls 61. The blanks 10 are deposited into this bin 42 by the conveyor 41 which receives the blanks 10 from a blank forming machine (not shown).

The blanks 10 are straightened out as they fall down and come to rest on a pair of opposed retractable retainer bars 62 each connected to and under the control of a pair of solenoids 63. The retainer bars 62 have a pair of rearwardly extending legs 64 extending therefrom each of which have slots 66 adapted to receive bolts 65 in order to insure that the retainer bars 62 move rectilinearly inwardly and outwardly.

The blanks 10 are deposited on the retainer bars 62 and during their downward travel they are straightened out by standards 60 and 61. As each blank 10 rests on retainer bars 62 the solenoids 63 pull the retainer bars 62 inwardly and apart from each other and the blank 10 will drop to the blank indexing mechanism 43 located therebelow.

BLANK INDEXING MECHANISM

The indexing mechanism 43 is shown in detail in FIGS. 5, 15, 16 and 17 and comprises standards 81 and opposed frame members 82.

Each frame member 82 is provided with a pair of spaced feed disc assemblies 70. Each feed disc assembly comprises a shaft 71 having vertically spaced upper and lower feed discs 72 and 73, respectively, thereon. The shaft 71 and the feed discs 72 and 73 are rotated by a pair of solenoids 74 through a slide 75 and an upstanding pin 76 which is eccentrically connected to feed disc 72. When the slide 75 is moved in one direction, the feed discs are rotated about 90° in one direction and when the slide 75 is rotated in the opposite direction, the feed discs are rotated 90° in the other direction.

The lower disc 73 has an extending, curved article-supporting portion 77 and a straight cutaway feed portion 78. The upper feed disc 72 is also provided with extending, curved-article-supporting portion 79 and straight cutaway feed portion 80. The cutaway feed portions 78 and 80 of discs 73 and 72, respectively, are fixed approximately at right angles to each other so that as the slides 75 are moved back and forth, the supporting portions 77 and 79 and the feed portions 78 and 80 of discs 73 and 72 are alternately moved into and out of operative position.

As the blanks 10 fall into the indexing mechanism 43, they are stacked on article-supporting portions 77 of lower discs 73 which are in operative position in the vertical path of the blanks 10 (FIG. 17). At this point the article-supporting portions 79 of the upper discs 72 are in retracted position and the cutaway feed portions 80 are in operative position allowing the blanks to pass the feed disc.

When the lowermost blank 10 is to be fed, the disc assembly 70 is rotated by movement of slides 75 so that the inwardly extending article-supporting portions 77 will be moved inwardly away from beneath the lowermost blank 10 to release it since the cutaway portion 78 is presented to the blank. Simultaneously, however, the article-supporting portion 79 of the upper disc 72 is moved into the path of the stack so that the rest of the blanks 10 are supported thereby. As the feed disc assemblies 70 are again rotated by the movement of the slides 75 back to their original position the article-supporting portions 79 of the lower disc 73 are moved back into the paths of the stack so that the stack of blanks 10 is held in supported position until the next blank at the bottom is to be released.

In this manner, with each movement of slide 75, a single blank is dropped from the indexing mechanism 43 and is dropped into the feed plate 45 so that the blanks are fed one-by-one onto the feeding mechanism 44.

BLANK FEEDING MECHANISM

The blank feeding mechanism 44 of the present invention is shown in FIGS. 4, 5 and 18 through 23.

Each blank 10 is dropped from the indexing mechanism 43 onto a feed plate 45 therebelow which has a pair of spaced longitudinal slots 91 therein. A pair of pusher fingers 92 are provided each mounted on opposed reciprocating chains 46 driven by sprocket wheels 94 and extending into slots 91.

10 An arm 95 extends upwardly from each chain 46 (FIGS. 22 and 23) and a link 96 is provided having one end mounted on the free end of the arm 95 and the other end pivotally connected to the lower rear portion of the finger 92 at 97. The link 96 is provided with a slot 98 therein for a purpose which will be more fully explained hereinafter.

The upper rear portion of the finger 92 has a lever 99 pivotally mounted thereon at 98 which extends rearwardly therefrom and which is positioned in the slot 91 in the feed plate 45. A guide finger 93 extends downwardly from the upper lever 99 into the slot 98 in the lower link 96. Thus, whenever the feed finger 92 is moved forward the lower link 96 is pushed forward so that the finger 92 is rocked clockwise around pivots 97-98 and raised through and beyond slot 91 above the level of the feed plate 45 (FIG. 23) and when the feed finger 92 is moved in a rearward direction the lower link 96 is pulled back and the finger 92 is rocked counterclockwise around pivots 97-98 so that the finger 92 is lowered within the slot 91 and below the level of feed plate 45 (FIG. 2).

When a blank 10 is dropped onto the feed plate 45, each feed finger 92 is in its rearward position (FIG. 22) approximately midway of the blank 10 and underlying the openings 21 therein. As the fingers 92 start to move forward by movement of chain 46, each finger 92 will be raised and will protrude beyond the upper surface of the plate 45 and into the openings 21 so that each finger 92 strikes the bearing surfaces 20 to push the first frame 16 of the blank 10 under the cutter mechanism 47, as shown in FIG. 23.

The fingers 92 are then pulled back by the reverse movement of the chain 46 and during this rearward motion the fingers 92 are lowered so that they do not interfere with the blank 10. After the fingers 92 reach their rearward position, the chain 46 reverses direction and moves again in a forward direction again to give a second stroke. Upon the second stroke the fingers 92 are again raised so that they strike the bearing surfaces 21 of the blank 10 to move the second frame of the blank 10 beneath the cutter mechanism 47.

Thus with every blank 10 that is dropped on the feed plate 45, the fingers 92 are moved forward twice in order to move frames 16 and 17 beneath the cutter mechanism 47.

CUTTER MECHANISM

As indicated above, each frame 16 or 17 of the blank 10 is successively positioned under the cutter mechanism 47 which is shown in FIGS. 3, 4, 7 and 22 through 28. 60 The cutter mechanism 47 comprises a knife assembly 100 which is positioned in an opening 103 in the feed plate 45. The knife assembly 100 has a plurality of notches 101 therein with a portion within the notches 101 being angled to form a series of knife blades 102 (FIGS. 25, 27 and 28). Normally, the upper edges of the knife assembly 100 are located beneath the top surface of feed plate 45 in order to permit the blanks 10 to be positioned thereover. However, after the blank is in position the feed plate 45 is adapted to be lowered to expose the edges of the knife assembly and cause it to protrude beyond the knife blades 102 (FIGS. 25, 27 and 28).

An upper punch plate 104 is positioned above the opening 103 and is adapted to be lowered therethrough 75 by a punch lowering mechanism 105. The punch plate

104 has a plurality of openings 116 therein for a purpose which will be more fully described hereinafter. The punch lowering mechanism 105 includes a carriage plate 106 movable therewith and having fork lever 107 (FIGS. 3, 4 and 7) pivotally mounted thereon by a pin 108. The fork lever 107 has a pair of pusher rods 109 journaled thereto by pin 110. The pusher rods 109 are mounted on feed plate 45 so that when they are depressed the feed plate 45 is also depressed.

The pusher rods 109 are controlled by a cam wheel 111 mounted on pin 110 and located in a cam slot 112 in arm 113 extending upwardly from carriage plate 106 and connected to the punch plate 104. The cam slot 112 has a vertical portion 114 and a lower inwardly angled portion 115 (FIG. 3). Upon depression of carriage plate 106 and the cutter punch plate 104 the cam wheel 111 is first acted on by the angled portion 115 of the cam slot 112 so as to depress the pusher rods 109 slightly and lower the feed plate 45. The cam wheel 111 is then acted on by the vertical portion 114 of the cam slot 112 so that although the cutter punch plate 104 is lowered, the lowering of feed plate 45 stops. In other words, upon the downward motion of the punch lowering mechanism 105, the feed plate 45 is lowered a slight distance and stops but the cutter punch plate 104 is lowered to the full extent of the stroke of the punch lowering mechanism 105.

The frames 16 and 17 of the blank 10 are successively moved beneath the punch plate 104 when the feed plate 45 is in its raised position and knife assembly 100 is retracted so that the blank 10 clears the knife assembly 100. The blank is so positioned that webs 18 in each frame 16 and 17 which join the spoons 3 to the border 11 of the blank overlie the notches 101 in the cutter assembly 100.

When the cutter punch plate 104 is depressed, the feed plate 45 moves down slightly so that the cutter assembly 100 is exposed and protrudes beyond the opening 103 and webs 18 in the frame 16 or 17 in blank 10 are inserted into the notches 101 in the cutter assembly 100 and overlying the knife blades 102. In this position, the downward movement of the feed plate 45 stops but the downward movement of the cutter punch plate 104 continues until it severs the webs 18 and releases the spoons 1.

The severed and released spoons 1 will drop down into the receptacle 48 and are guided downwardly by guide pin assembly 49, as will be explained hereinafter below.

The cutter punch plate 104 is then raised which in turn raises the feed plate 45 so that the cycle can be repeated when a new frame is positioned beneath the punch plate 104.

TAKE-OUT MECHANISM

After the second frame 17 of blank 10 is cut, the empty blank 10 is removed by a pair of rotatable take-out rollers 85 pivotally mounted on rod 86 through arms 87. The empty blanks 10 come into contact with take-out rollers 85 when feed plate 45 is raised. The take-out rollers 85 pull out the empty blanks and place them in a bin 88 for possible subsequent reprocessing.

GUIDE PIN MECHANISM

The guide pin mechanism 49 for guiding the spoons 1 down into the receptacle 48 is shown in FIGS. 9 to 12, 22 to 24, 26, 29 and 30 and comprises a pin plate 120 having a plurality of upwardly extending front guide pins 121 and a plurality of upwardly extending thinner rear guide pins 122 mounted therein. The guide pins 121 and 122 normally extend through the bottom of the receptacle 48 and beyond its upper edge to a plane slightly below the plane of the feed plate 45.

The front guide pins 121 are in close adjacency to each other and spaced apart a distance sufficient to brush against the bearing surfaces 4 of each spoon 1. Each rear guide pin 122 is linearly between the front guide pins 121 and is adapted to enter the opening 5 in the handle portion 3 of the spoon 1. It will thus be seen that the guide pins

121 and 122 cooperate together to guide the spoons 1 downwardly into the receptacle 48 after they are severed by the cutter.

The pins 121 and 122 extend upwardly through openings 123 in guide plate 124 and through bottom wall of receptacle 48 to approximately a level slightly below the level of the feed plate 45. As indicated above, the cutter punch 104 has a plurality of openings 116 which are coaxial with the pins 121 and 122 so that the pins 121 and 122 are inserted within openings 116 when the cutter punch plate 104 is lowered.

In order to keep the thinner rear guide pins 122 aligned and prevent them from vibrating, each rear guide pin 122 is held in position by a permanent magnet 127 mounted in a plurality of rods 128 slidable within a block 129 mounted on a gauge plate 130. Each rod 128 has a curved pin-receiving face 131 at the front end and is mounted at the rear end to a slide carriage 132. The slide carriage 132 is provided with rollers 133 and 134 adapted to ride on rails 135 and 136 and is spring-pressed forward by means of springs 137.

The slide carriage 132 is adapted to be moved rearwardly against the action of spring 137 by cam blades 138 having cam surfaces 139 thereon. The cam blades 138 depend from plate 106 and are moved downwardly therewith to cause the cam surfaces 139 to act on and move slide carriage 132 and rods 128 rearwardly away from pins 122. This releases the pins 122 from the magnetic attraction of magnets 127 and moves the rods 128 out of the path of spoons 1 to permit the spoons 1 to drop down into the receptacle 48.

With this structure the pins 121 and 122 are normally in their raised position and the pins 122 are held against vibration by the magnets 127 in rods 128. When the plate 106 and cutter punch plate 104 is lowered to sever the webs 18 on the spoons, the cam blades 138 are also lowered to move the slide carriage 132 and rods 128 rearwardly to free pins 122. The pins 121 and 122 enter the openings 116 in the plate 104 in order to permit the plate 106 to be lowered to its full extent.

When the feed plate 45 is lowered a pair of opposed aligning blades 118 extending upwardly from a plate 130 are exposed and enter the centering slots 19 in the border 11 of each frame of blank 17 to hold each frame centered during the cutting operation. The aligning blade 118 extends above the top of guide pins 121 and 122 in order to permit it to first center the blank 10 before the pins 121 and 122 become effective.

The severed spoons 1 slide along the guide pins 121 and 122, past the retracted rods 128 until they reach the bottom of receptacle 48. The spoons 1 maintain their alignment while they travel downwardly so that they are deposited in the receptacle 48 with the bowls of adjacent spoons facing in opposite direction to permit all of the area to be utilized.

This operation continues as each frame on blanks 10 is presented to cutter punch plate 104 until the receptacle 48 is full. When this happens, the pin plate 120 and pins 121 and 122 are lowered and completely withdrawn from 60 within the receptacle 48 in order to permit the receptacle 48 to be moved out from beneath the cutter mechanism 47 as will be referred to in greater detail hereinbelow.

RECEPTACLE

65 The receptacle 48 is shown in FIGS. 29 to 37 and comprises a hollow inner container 150 having an open top, side walls 151 and a bottom wall 152. The bottom wall 152 is provided with a wide central slot 153 to receive guide pins 121 and a pair of narrow slots 154 to receive 70 guide pin 122. The bottom wall 152 extends beyond the side walls 151 and has an upstanding outer sleeve or jacket 155 extending upwardly therefrom. The outer jacket 155 is shorter than the side walls of the inner container 150 so that its edges terminate below the upper edges of the inner container 150. The outer jacket 155 is

spaced from the walls of the inner container 150 to form a space 156.

The upper edge of the sleeve 155 has a flange 157 which is rotatably mounted on a drive plate 158 by means of journal 159 adapted to be moved forward by a piston 160 and to be maintained in upright position by guide rods 161. An elongated gear bar 162 having gear teeth along its length is adapted to rotate and invert the receptacle around journal 159.

When the receptacle 48 is filled with spoons and after the guide pins 121 and 122 have been removed, the piston 160 moves the receptacle 48 outwardly beneath the carton 31 (FIG. 33). The carton 31 is then lowered and the flaps 32 of the carton 31 strike the edge of the outer sleeve 155 and are moved against the side walls 33 of carton 31. Continued lowering of the carton 31 inserts the side walls 33 and the flaps 32 into the space 156 between the inner container 150 and the outer sleeve 155 of the receptacle 48 (FIG. 35).

In this position, a rotating mechanism rotates the gear bar 162 and the receptacle 48 with the container 31 mounted thereon is rotated 180° to invert the receptacle 48 and the carton 31 (FIG. 36). This transfers the spoons 1 from the receptacle 48 to the carton 31 without disturbing their alignment to each other. Thus the spoons are deposited in the carton 31 with adjacent spoons having their bowl portions facing in opposite directions. The stacks of spoons maintain this alignment after being transferred to the carton 31.

The filled carton 31 is removed from the receptacle 48 and the receptacle 48 is again inverted 180° to bring it back to its original position. The receptacle is then withdrawn to a position beneath the punch so that the filling cycle can be repeated.

CARTON FEEDING MECHANISM

The carton feeding mechanism 50 for feeding the carton 31 comprises a carton-holding bracket 170 in which the carton 31 is placed with its flaps 32 extending outwardly and held in place by plates 171. A pair of downwardly extending pusher blades 172 are provided and are spaced apart a distance substantially equal to the spacing between slots 154 in bottom wall 152.

After receptacle 48 has been moved out and placed beneath the carton 31, the pusher blades 172 are lowered to strike the carton 31 and lower it over the receptacle 48 with the flaps 32 and the side walls 33 of the carton positioned in the space 156 between the inner container 150 and the outer sleeve 155.

The pusher blades 172 are then raised and the receptacle 48 with the carton 31 thereon is inverted so that the spoons 1 are transferred from the receptacle 48 to the carton 31. The pusher blades 172 are then lowered again and are moved through the slots 154 in the bottom wall 152 of the receptacle 48 and apply pressure to the stacked spoons 1 to push the filled carton 31 out of the receptacle 48.

After this operation is completed the pusher blades 172 are again raised and the receptacle 48 is retracted to a position beneath the cutter 47 to start it to be filled.

OPERATION

The operation of the invention will be understood from the above description but it will be summarized hereinbelow for convenience.

Blanks 10 with two frames 16 and 17 of spoons 1 are formed in a molding machine and are delivered to the blank dropping mechanism 42 by means of a conveyor 41. The blanks are fed by blank dropping mechanism 42 one-by-one into a blank indexing mechanism 43 by means of the slidable retainer bars 62 which are retracted to release each blank (FIGS. 13 and 14).

From the blank indexing mechanism 43 they are fed one-by-one onto a feed plate 45 by means of a plurality of rotating feed wheels 72 and 73 (FIGS. 15 to 17)

which have curved retaining areas and flat feed areas angled at about 90° to each other. When the wheels 72 and 73 rotate they drop the lowermost blank from the stack onto the feed plate 45.

5 A pair of feed fingers 92 controlled by a reciprocating chain 46 strikes the bearing surfaces 22 of the first frame 16 on blank 10 and moves the blank 10 forward until the frame 16 is positioned beneath the cutter punch 104. The feed fingers 92 are then withdrawn and are in position to feed the second frame 17 after the spoons have been severed from the first frame 16.

10 The cutter punch 104 is lowered and this carries with it the feed plate 45 which is lowered for a distance and then stops. Lowering the feed plate 45 causes aligning blades 118 to enter the centering slots 19 in the first frame 16 of the blank 10 and causes the webs 18 to enter the slots 101 in knife assembly 100 and rest on knife edges 102. The pins 121 and 122 also extend through the blank 10 and assume their aligning position with each pair of adjacent pins 121 straddling bearing surfaces 44 on spoons 1 and pins 122 entering opening 5 in spoon 1.

15 As the cutter punch 104 continues to be lowered, the pins 121 and 122 enter the openings 16 in the cutter punch 104 and the magnet carrying rods 128, which normally hold the pins 122 steady are moved away from the pins 122 by means of the cam blades 138. The pins 121 and 122 are maintained in aligned position by being located in the openings 116 in the cutter punch 104.

20 The downward movement of the cutter punch 104 severs the webs 18 and the spoons 1 will fall down along the guide pins 121 and 122 and drop onto the bottom 152 of the receptacle 48 in the same position as they were when they were on the blank 10, i.e. with the bowl portions 2 of adjacent spoons facing in opposite directions, since 25 they are guided and kept aligned in this position by guide pins 108 for the full length of their downward travel.

25 The cutter punch 104 is then raised and feed plate 45 is also raised. The magnet holding rods 128 are placed back into position by spring 137. The feed fingers 92 are again moved forward and move the second frame 17 of the blank 10 beneath the cutter punch 104 and the operation is repeated. The empty blanks are removed by the take out rollers 85 and deposited into a bin 88.

30 Thus the receptacle will be filled with stacks of spoons, each stack of which is aligned so that the bowl portions of adjacent spoons face in opposite directions.

35 When the receptacle 48 is filled with spoons 1 the pins 121 and 122 are withdrawn from within the receptacle 48 and the receptacle is moved out from beneath the cutter punch 104 to a position beneath the carton 31. The carton 31 is then lowered over the receptacle 48 by means of pusher blades 172 which are then raised.

40 The receptacle 48 and the carton 31 are inverted 180° so that the spoons are transferred from the receptacle 48 to the carton 31 without losing their alignment to each other. The pusher blades 172 are then lowered again in order to push the filled carton 31 out of the receptacle 48. The receptacle 48 is again inverted to its original position and withdrawn to a position beneath the cutter punch 60 104 so that it can start to fill with spoons again.

45 It will be understood that although the application has been described in connection with spoons, it is obvious that the present application will work for forks, knives and any other articles with which it is desirable to have proper aligning during shipping, handling and storage. Thus, whenever the word "spoon" is used herein, it is intended that not only a spoon but also a fork, a knife or any other article which is capable of being aligned be included in the term.

70 It will also be understood that although it is desirable that the blanks 10 have two frames of spoons it is possible to operate the present invention with blanks having a single frame or with blanks having more than two frames.

Furthermore, while the preferred embodiment of the invention shows the spoons with their handles facing in opposite directions, it may be just as desirable for certain articles such as knives, that the handles face in the same direction and the present invention is intended to cover such a contingency.

It will thus be seen that the present invention provides an improved packaging machine and method which permits more articles to be packaged in a container per unit volume than heretofore possible and which may be packaged in a predetermined uniform fashion automatically and at greater speeds. Furthermore the resulting carton has a greater number of articles therein per unit volume than heretofore possible which results in greater savings in handling, shipping and storage costs.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

Having thus described our invention, we claim:

1. A machine for packaging articles comprising a cutter assembly, means for presenting a blank of articles to said cutter assembly, means in said cutter assembly for severing said articles from said blank, receptacle means beneath said cutter assembly, said receptacle means having an open top, means for guiding said severed articles into said receptacle means through said open top, said guiding means comprising aligning means for maintaining the relative positions of said articles to each other during the travel of the articles from said cutter assembly into the receptacle means, means for moving said filled receptacle from under said cutter means, means for telescopically mounting a carton means over the open end of the receptacle means and means for inverting said receptacle and carton means to thereby transfer said articles from said receptacle means to said carton means without changing the relative position of the articles to each other.

2. A method of packaging articles comprising forming a blank with said articles in a predetermined orientation relative to each other, severing said articles from said blank, guiding said severed articles into receptacle means positioned below said blanks, maintaining the relative positions of said articles to each other during the travel of the articles from said blank into said receptacle means, moving the receptacle means from beneath the severing means, telescopically positioning carton means over said receptacle and inverting said receptacle means and said carton means to transfer said articles from the receptacle means to the carton means while maintaining the relative positions of the articles to each other during said transfer.

3. A machine as claimed in claim 1, wherein said guiding means comprise a plurality of guiding pins.

4. A machine as claimed in claim 3, wherein said guiding pins are adapted to engage said articles to each other.

5. A machine as claimed in claim 4, wherein the articles are provided with bearing surfaces and wherein said guiding pins engage said bearing surfaces.

6. A machine as claimed in claim 4, wherein the articles are provided with an opening therein and wherein said guiding pins are adapted to extend into the opening.

7. A machine as claimed in claim 4, wherein the articles have a pair of opposed bearing surfaces adjacent the front end and an opening adjacent the rear end and wherein said guide means comprise a pair of opposed guide pins adapted to engage said bearing surfaces and a rear guide pin adapted to enter the opening in said article.

8. A machine as claimed in claim 7, wherein said receptacle means is positioned below said cutter means and wherein said guiding pins extend through the bottom of said receptacle means.

9. A machine as claimed in claim 8, wherein means are provided for withdrawing said pins from said re-

ceptacle means when the receptacle means is filled with articles.

5 10. A machine as claimed in claim 9, wherein means are provided to move a carton into encasing position relative to the receptacle and wherein means are provided to invert said receptacle and said carton to transfer the articles from the receptacle to the carton without altering the alignment of the articles to each other.

11. A machine as claimed in claim 10, wherein at least some pins are held against vibration by retractable magnetic means.

15 12. A machine as claimed in claim 11, wherein said magnetic means comprise a plurality of slidable rods and wherein said cutter means is provided with cam means to move said rods to a retracted position when the cutter means is lowered to sever the articles.

13. A machine as claimed in claim 12, wherein feeding means are provided to feed said blanks to a position beneath said cutter means, said feeding means comprising a 20 feed finger movable along a feed plate.

14. A machine as claimed in claim 13, wherein said feed plate finger is provided with a slot adapted to receive said feed finger and wherein said means are provided to lower said feed plate to expose said feed finger for feeding 25 the blanks to the cutter mechanism.

15. A machine as claimed in claim 14, wherein the means for lowering said feed plate are operatively connected to the mechanism for lowering the cutter plate.

30 16. A machine as claimed in claim 15, wherein said cutter plate is provided with a standard having a cam slot therein and wherein said cam slot has an angled portion and a straight portion, said feed plate being connected to a cam movable within said cam slot whereby the action of the angled portion of the cam slot lowers the feed plate.

35 17. A machine as claimed in claim 16, wherein a knife assembly is provided beneath the cutter plate and wherein said knife assembly is exposed when the feed plate is lowered.

40 18. A machine as claimed in claim 17, wherein the knife assembly comprises a plurality of notches having knife edges therein, said knife edges being adapted to enter into the webs of the blank when the feed plate is lowered.

45 19. A machine as claimed in claim 18, wherein a centering blade is provided which is adapted to enter a centering slot in the blank when the feed plate is lowered.

50 20. A machine as claimed in claim 19, wherein said pins are mounted on a pin plate and are adapted to extend through the bottom of the receptacle means and wherein means are provided to lower said pin plate and said pins and to withdraw them from the receptacle after the receptacle is filled with articles.

21. A machine as claimed in claim 20, wherein openings are provided in said cutter plate aligned with said pins and adapted to receive said pins.

55 22. A machine as claimed in claim 21, wherein pusher blades are provided to push said carton over the receptacle means.

60 23. A machine as claimed in claim 22, wherein said pusher blades are adapted to be raised and means are provided for inverting the receptacle and the carton and wherein means are provided for lowering the blades in order to move the filled carton out of the receptacle.

65 24. A machine as claimed in claim 23, wherein said inverting means comprises a shaft having gear teeth thereon.

70 25. A machine as claimed in claim 24, wherein the feed finger is a rockable finger having upper and lower rear end portions, a lever extending from each end portion thereof so that the finger will rock upwardly when moved forward and will rock downwardly when moved rearwardly.

26. A machine as claimed in claim 25, wherein said straightening means comprises a pair of retainer bars which are moved apart to release a blank mechanism.

27. A machine as claimed in claim 26, wherein said indexing mechanism comprises a plurality of feed rollers having a feeding section and a retaining section and wherein means are provided to rotate said feed rollers in order to alternately expose the feed sections to feed blanks one by one onto said feed plate.

28. A machine as claimed in claim 27, wherein said rotating means comprise an eccentrically located pin controlled by slidably bars.

29. A machine as claimed in claim 28, wherein take off rollers are provided to remove empty blanks from beneath the cutter mechanism.
